HOISTING MECHANISM

Filed Oct. 28, 1925

UNITED STATES PATENT OFFICE

ROBERT C. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Original application filed December 18, 1923, Serial No. 681,432. Divided and this application filed October 28, 1925. Serial No. 65,445.

While my invention relates generally to improvements in hoisting mechanisms, it is directed more particularly to improved motor and drum supporting means for hoisting mechanisms.

The hoisting mechanism of the type herein disclosed comprises generally a base, a motor, supporting means therefor carried by the base, and a drum driven by the motor. In such mechanisms the motor is herein preferably of the electric type and, as is usual with such types of motor, lead wires extend substantially radially from the periphery of the motor casing. Inasmuch as the drum partially surrounds the motor casing, it is essential that improved means be provided for allowing access to the lead wires. It is accordingly an object of my invention to provide such improved means and in a more specific aspect 20 of the invention to provide means whereby the lead wires may extend through the motor supporting means. A further object is to provide improved means whereby the motor may be substantially freely longitudinally removed from the supporting means without any substantial interference from the lead wires which extend through the supporting means. A further object is to provide means for permitting the longitudinal removal or 30 insertion of the motor from the supporting means and yet permit a suitable operative relation between the supporting means, motor and drum.

In the accompanying drawings I have shown for purposes of illustration one form which my invention may assume in practice.

In these drawings,—

Fig. 1 is an elevation of the hoisting mechanism partly broken away to show details of 40 construction.

Fig. 2 is a fragmentary longitudinal section of the motor supporting means showing means permitting removal of the lead wires therefrom.

45 The disclosure in this application is the same as that in my copending application, Serial No. 681,432, filed Dec. 18, 1923, of which this application is a division.

Inasmuch as the invention herein resides in 50 the means for permitting removal of the mo-

tor with its projecting lead wires, the hoisting mechanism in general will be only briefly described. A base 1 is provided at its central portion with an upstanding standard 2 forming a split clamp and provided with a bore 3 within which a motor 4 is insertable. The motor preferably has a close slidable relation to the bore walls while no clamping action is being exerted. The standard 2 is split as at 5 to permit passing a pair of bolts 6 through lugs 7 formed on the free ends of the standard 2 to clamp the motor within the bore 3. The drums 8 and 9 are journaled at their adjacent ends on the periphery of the motor casing as by roller bearings 10 and 11 while the remote drum ends are journaled in suitable standards 12 and 13. Suitable gearing is provided between the armature shaft 14 and the drums.

The motor herein shown is preferably of the electric type having lead wires projecting from the casing; but it will of course be understood that many other types of motor might be used which, if having a generally similar characteristic such as a projecting element, would permit utilization of my invention. The standard 2 has a radial boss 15 carrying a terminal plug 16 to which may be connected the lead wires 17 which extend substantially radially from the housing of the motor 3. To permit insertion or removal of the motor there is formed in the boss 15 a chamber 18 having communication with a slot 19 extending to one side of the standard 2. By this construction, the lead wires (should an electric motor be used) or other laterally projecting part of the driving motor are accommodated by the passageway or slot 19 when it is desired to slip the motor out of its clamp. The lead wires are made extra long so that assembly with part 16 is facilitated. The procedure of assembly consists in slipping the motor into place, at the same time directing the lead wires out through the chamber 18; attachment is made of the wires to the proper terminals on the plug 16; and then the wires 17 are pushed into place in the boss 15. Tightening of the clamp by drawing up the bolts 6 secures the motor firmly in place. When it is desired to

take the hoisting mechanism apart, the bolts or screws fastening the standard 13 to the base 1 are first removed together with the portion of the brake mechanism which is secured to the base. The standard 13 and the drum 9 are then slipped from their position by longitudinal movement to the left. The ring 20 may now be removed; and loosening of the bolts 6 will permit the motor casing to be moved out of the clamp or standard 2. It is of course obvious that the lead wires 17 must first be disconnected from the plug 16 so as not to interfere with the removal of the motor. These wires pass without difficulty 15 along the slot 19 which has been provided in the clamp 2.

In order to present a substantially continuous bearing surface and also to close the open end of the slot 19 for prevention of oil leakage through the slot 19, there is provided a removable annular ring 20 adapted to slidably engage the motor housing periphery adjacent the side of the standard 2 thereby to close the open end of the slot 19. An annular 25 groove 21 is provided in the ring to receive a suitable packing 22 while the roller bearing 11 engages the outer side of the ring at points spaced inwardly from the packing 22. The drum has a flange 23 overlying the ring 20. 30 While the above construction is utilized on only one side of the central standard, this is because the motor need be removed from only one side of the standard although it is obvious that if for any reason it should be desired to remove the motor from either side 35 of the standard, this construction could be duplicated on the other side thereof. It will also be noted in Fig. 2 that the drum flange 23 abuts the standard 2 at a point radially 40 beyond the slot 19 so that, should it be desired to dispense with the ring 20, the slot 19 would nevertheless be closed. It is of course clear that this construction is also adapted for a single drum hoist.

45 While I have in this application specifically described one form which my invention may assume in practice, it will be understood that this form of the same is shown for purposes of illustration and that the invention may be 50 modified and embodied in various other forms without departing from its spirit or the scope of the appended claims.

What I claim as new and desire to secure by Letters Patent is:

55 1. A driving mechanism comprising a motor having a housing with an element projecting outwardly therefrom, and means for rigidly supporting said motor having an opening therein of substantially the same outline and size as said housing and arranged to receive said housing when the latter is moved into said opening axially of said opening, said supporting means having also therein an opening into said opening and also through 60 the side of said supporting means through

which said housing is inserted, a recess to receive said outwardly projecting element as said housing is moved into said supporting means axially of the opening therein.

2. A driving mechanism comprising a motor having a housing and an element projecting outwardly therefrom, supporting means for said motor having a bore adapted to receive longitudinally said housing, said supporting means providing a passageway for entrance of said element by the same longitudinal movement, and means placed in position after insertion of said housing to close said passageway. 70

3. A driving mechanism comprising a motor having a housing and an element projecting outwardly therefrom, supporting means for said motor having a bore adapted to receive longitudinally said housing, said supporting means being grooved to provide a path for entrance of said element by the same longitudinal movement, and an annular member placed in position after insertion of said housing to cover the end of said groove. 80

4. A driving mechanism comprising a motor having a housing and an element projecting outwardly therefrom, and supporting means for said motor having an opening adapted to slidably receive said housing by longitudinal movement, said supporting means providing a passageway for entrance of said element by the same longitudinal movement, and having also a lateral opening to permit access to said element through said supporting means. 90

5. A driving mechanism comprising a motor having a housing and an element extending radially therefrom, and supporting means therefor adapted to receive longitudinally slidably said housing and provided with a longitudinal slot to receive said element, said supporting means also being provided with a chamber communicating with said slot. 105

6. A driving mechanism comprising a motor having a housing, said housing having lead wires extending radially therefrom, and supporting means for said housing adapted to receive longitudinally slidably said housing and provided with a longitudinal slot to receive said lead wires, said supporting means also being provided with a radially extending chamber communicating with said slot and said supporting means providing a mounting for a terminal plug adjacent said chamber to provide for convenient connection with the lead wires. 110

In testimony whereof I affix my signature.

ROBERT C. OSGOOD.
